MEANS TO PRECLUDE WIND FLEXING OF
A STORM SASH
John Bruno, 495 E. 22nd St., Paterson, N.J.
Filed July 6, 1959, Ser. No. 825,129
6 Claims. (Cl. 20—55)

My invention relates to storm sash assemblies for installation within window or door casings or the like of buildings and more particularly to means for securing the storm sashes anchored to their adjacent frames against bellying.

Heretofore, considerable difficulty has been experienced in maintaining storm sashes, especially relatively long windows and doors, properly sealed and weather insulated within the so-called double or triple track type of storm sash frames for the reason that, while each storm sash is supported against outward movement throughout its length by a flange of the frame engaging its outer face, the inner face of the sash is not similarly supported because it is maintained within its frame only by means of pins which project from the ends of the sides of the sash into side channels of the frame, thus enabling wind pressure to belly or bulge the sash between its ends, where there are no pins, and create a loose fit between the sash and frame for the admittance of draft and weather and which bellying often results in breakage of the sash, it being understood that the pins are arranged at the ends of the sash in order that a pair of the pins may be retracted to permit pivoting of the sash into the building and tilting thereof to dispose the other pins out of the channels.

My invention overcomes the foregoing difficulties, disadvantages, and undesirable features inherent in the prior art, especially in relatively long windows and doors, it being one of the objects thereof to provide a sash equipped with anti-bellying means operable for anchoring the sash to the window frame against bellying and thereby maintain a weather seal and tight fit.

Another object of my invention is to provide anti-bellying means of the foregoing described character which may be applied to sashes already in use without substantial modification thereof.

An important object of my invention is to provide anti-bellying means of the foregoing described character which is simple in construction, durable in use, efficient in operation, and economical in manufacture.

With the above and other objects in view, as will hereinafter appear, the invention consists in the combination and arrangement of parts hereinafter set forth and illustrated in the accompanying drawings from which the several features of the invention and the advantages attained thereby will be readily understood by those skilled in the art.

Referring to the drawings wherein like reference characters designate like parts throughout the several views:

FIGURE 1 is a front view of my invention as applied to a storm sash assembly secured to a window casing of a building and looking outwardly from within the building;

FIGURE 2 is a detail fragmentary sectional view on an enlarged scale and taken on the line 2—2 of FIGURE 1, the anti-bellying means being disposed in anchored relation with the frame;

FIGURE 3 is a view similar to FIGURE 2 but with the anti-bellying means being disposed in released position with the frame to permit removal of the sash from the frame;

FIGURE 4 is a perspective view of the anchor; and

FIGURE 5 is a fragmentary end elevation of one of the sides of the sash.

In teaching my invention, as illustrated in the drawing, I employ a window casing 7 of a building 8 or the like and mount within said casing, in fixed relation therewith,

2

the framing 9 of a storm sash assembly 10, the latter being of a suitable metal, for instance, extruded aluminum, and equipped with vertical slidable sashes S constituting a weather-guard. In the present disclosure, the assembly is of the so-called triple track type with the screen unit being removed in the interest of clarity, it being understood that the double track type may be employed if the screen unit or sash is to be seasonably removed. As viewed in FIGURE 1 of the drawing, the framing 9 has its interior or lee side disposed inwardly of the building while its exterior or weather side is disposed outwardly of the building. The weather-guard or sashes S are each provided with laterally projecting pins 11 at their upper and lower ends with a pair of the pins being retractable against spring tension. Each sash is also provided with a glass pane 12 secured within a frame 13 which includes channel-like side members 14 having slots 15.

Each of the side members 14 are defined by inner and outer walls 16 and 17, respectively, structurally integrally connected together, at coincident ends, by a side wall 18, the opposite end of the outer wall 17 being provided with a kerf 19 on its inner face in which an adjacent portion of the pane 12 is disposed and secured in sealed relation therewith. The opposite end of the inner wall 16 is formed with an inwardly disposed and lengthwise extending projection 20 disposed within a groove formed in a glazing spline 21 having fingers 22 disposed in compressed relation with the pane 12 for securing the pane fixed within the kerf. The inner wall 16, adjacent the wall 18, is formed with an inwardly offset portion 23 and constitutes a seat for a purpose hereinafter described.

Opposite the portion 23 the outer wall 17 of each member 14 is formed on its outer face with a dovetail groove 24 in which is mounted a sealing gasket 25 of suitable material, for instance, wool pile, and on its inner face with a rib 26, the gasket and rib extending throughout the length of each wall 17.

The framing 9 of the assembly 10 is fashioned with a ternary of side rails 27 adjacent each side of the casing and with the rails being arranged in a stepped relation wherein the width between the innermost rails is progressively greater with respect to the outermost and intermediate rails to permit removal of the sash and screen unit inwardly within the building as is the usual practice.

Each rail 27 is formed with a channel 28 defined by front and rear walls 29 and 30, respectively, connected together by an end wall 31, the wall 29 being provided on its inner face, remote from the wall 31, with a lengthwise extending rib 32. As illustrated in FIGURES 2 and 3 of the drawing, the rear wall 30 is provided with an extension 33 constituting a component of the respective side rail and serving as a stop for receiving thereagainst the gasket 25 to effect a seal between the sash and framing. When the sashes are disposed within the framing, the pins 11 extend into the channels 15 and engage the walls 29 to maintain the sashes assembled within the framing against displacement into the building and in a manner permitting sliding movement of the sashes within the confines of the rails. Each of the sashes is removed from within the building by operating the aforementioned retractable pins to their retracted positions, pivoting one end of the sash outwardly into the building and tilting the sash sufficiently to dispose the pins, at the other end of the sash, out of the channels and the sash out from between the rails. A reverse operation effects assembly of the sashes within the framing. Inasmuch as the foregoing described assembly is of an ordinary construction and does not constitute the invention per se, a more detailed disclosure of the assembly is not deemed necessary.

When the sashes are assembled between their respective side rails, it will be noticed that a relatively large dis-

tance exists between the top and bottom pairs of pins of each sash and while each wall 30 or its extension 33 functions to preclude outward displacement of the sashes from pressure within the building, the only means for precluding displacement of the sashes inwardly into the building, by pressure from without the building, are the pins. In many installations, due to relatively strong winds and the like, the sashes tend to belly or bulge inwardly between their upper and lower ends with the result that the gaskets 25 are rendered inoperative in zones between the ends of the sashes thus permitting a draft into the building from without. In some instances, the degree of bellying is such that the panes are often broken. This condition is especially prevalent in instances of relatively long door and window sashes.

In order to preclude the aforementioned bellying of the sashes, I provide each of said sashes with at least a pair of anchoring devices 39 mounted on the sash. Each device comprises a one-piece elongated body or bar 40 formed at one end with a right-angularly disposed finger-piece 41 and at the opposite end with an offset and parallel extending arm 42 as clearly illustrated in the drawing. Each device has its body 40 disposed in adpressed relation with the pane 12 and extending between the pane and the spline 21, the latter being suitably fitted about the device to permit sliding of the device. In installing each of the devices 39 I form the wall 18, adjacent the device, with an elongated slot 43 through which the arm 42 operates. The slot 43 is formed by a suitable tool, for instance, a cope chisel, and in a manner wherein a cutout section is turned inwardly to provide a lip or seat 44 for accommodating the arm 42 and serving to limit the inward movement of the device by engagement with the offset portion 45 of the arm as illustrated in FIGURE 2 of the drawing.

In use, the sashes being equipped with the devices 39 and disposed within the confines of their respective side rails, each device is moved by the finger piece 41 towards the adjacent wall 31 and into the channel 28 and thus rides over the rib 32. When the devices are thus disposed in their extended positions, they serve to anchor the sashes to the framing and preclude bellying of the sashes between their ends by pressure from without the building. The devices may be moved to retracted positions to dispose the fingers 42 out of the channels 28 and thus permit the sashes to be removed from the framing in the ordinary manner.

From the foregoing, it will be apparent that my invention provides a simple, economical, and efficient means for preventing bellying or bulging of window sashes especially those of relatively long lengths and is equally useful for overcoming the same difficulties when applied to the panels of doors or the like. It is to be noted that the spline 21 is constructed of a suitable resilient material and, therefore, serves to maintain the body 40 in an adjusted position against the pane to prevent movement by vibration or the like, the spline also serving to engage the portion 45 to limit the retracting movement of the body 40. It will also be noted, as clearly disclosed in FIGURES 2 and 3, that while each of the fingerpieces 41 extends outwardly from the pane 12 of a respective sash, it is relatively short and terminates within the confines of the adjacent spline 21 to preclude engagement with the meeting rail of the other sash during raising and lowering of the sashes relative to each other.

Without further elaboration, the foregoing will so fully explain the invention that others may, by applying current knowledge, readily adapt the same for use under various conditions of service. Moreover, it is not indispensable that all the features of the invention be used conjointly since they may be employed advantageously in various combinations and subcombinations.

It is obvious that the invention is not confined solely to the use herein disclosed in connection therewith as it may be utilized for any purpose to which it is adaptable.

It is, therefore, to be understood that the invention is not limited to the specific construction as illustrated and described, as the same is only illustrative of the principles involved which are capable of extended application in various forms, and the invention comprehends all construction within the scope of the appended claims.

What I claim is:

1. In combination, a storm sash framing for incorporation within a casing defining an opening in a building; a storm sash having side members, a top member and a bottom member, and being removably secured within said framing; said framing having exterior and interior side rails, said exterior rails providing surfaces to support the side members of said sash, first members connected with the sash at opposite sides thereof adjacent the top member and detachably connecting said sash with the framing, second members extending from the sash at opposite sides thereof adjacent the bottom member and detachably connecting said sash with the framing, and an elongated bar movably mounted on each of the side members between said first and second members for movement into engagement with said interior rails to maintain said side members firmly against the surfaces of the exterior rails.
2. In combination, a storm sash framing for incorporation within a casing defining an opening in a building; a storm sash having side members, a top member and a bottom member, removably secured within said framing; said framing having exterior and interior side rails, said exterior rails providing surfaces to support the members of said sash, pivot means extending from the upper ends of the side members of said sash into the framing between the rails to maintain said sash within the framing, movable projections extending from the lower ends of the side members spaced from said pivot means, said projections being movable from extended positions in the framing, to maintain the sash in the framing, to retracted positions to permit removal of the sash from the framing, and an elongated bar movably disposed in each of said side members between said pivot means and said projections for movement into engagement with said interior rails to maintain said side members firmly against said exterior rails.
3. In combination, a storm sash framing for incorporation within a casing defining an opening in a building a storm sash, having side members, a top member and a bottom member, removably secured within said framing; said framing having exterior and interior rails, said exterior rails providing a surface to support the side members of said sash, pins extending from the side members at opposite ends thereof of said sash into said framing between the rails to maintain said sash within the framing, a pair of said pins being retractable to permit removal of said sash, an elongated vertical slot in each side member substantially midway thereof, a flexible spline cooperating with the members of the sash to secure a pane of glass therein, a flat bar slidably disposed in each of said side members and extending between the glass and the spline, and fingerpieces on said bars for sliding the bars through said slots into engagement with said interior rails to effect a sealing relation between the side members and said surface.
4. In combination, a storm sash framing for incorporation within a casing defining an opening in a building and having lee and weather sides, said framing having side rails formed with channels and lateral extensions on said weather side, a storm sash unit having side walls disposed within said framing adjacent said rails and in confrontation with said extensions, said unit adapted to be exposed to the weather and being readily removable from said framing solely from said lee side, said unit including a pane extending into said walls and having a leeward side and a resilient spline securing said pane to said walls on said leeward side, said unit having upper and lower ends equipped with retaining devices extending into said channels and coacting with said extensions

for maintaining said unit within said framing, said devices being displaceable out of said channels to permit said ready removal of said unit, each of said side walls being formed with a slot substantially midway between said ends and a stop adjacent said slot, and anchoring members disposed in adpressed relation with said pane and between the latter and said spline, said anchoring members extending into said side walls and slidably therefrom into said channels through said slots, respectively, to effect anchoring relation of said side walls with said rails to preclude bellying of said unit between said ends, by weather-pressure from outside of the building, said members being provided with fingerpieces disposed out of said walls, respectively, and operable for effecting sliding movement of said members, between said pane and spline into and out of said channels, said spline co-acting with said pane to maintain said members in said adpressed relation, said members having offset portions disposed within said walls, respectively, for engaging said stops to limit the movement of said members towards said side rails and said spline for limiting the movements of said members when operated out of said channels to prevent withdrawal of said members from between said pane and spline.

5. In a storm sash assembly of the class wherein a sash unit having side walls and inherently susceptible to lateral flexing in either direction between the ends of the walls is disposed within a frame unit effective to preclude the lateral flexing in one direction, the combination with a slidable bar member extending into each of the walls between its ends and having an anchoring offset end section encased within the respective wall and projectable therefrom into the frame unit for anchoring engagement therewith to preclude lateral flexing of the sash unit in the opposite direction when each of the members is so projected.

6. A sash anchoring member capable of being slidably encased within the side wall of a storm sash unit mounted within a framing effective for precluding trans-

verse flexing of the unit in one direction between its ends and in interposed relation with the pane and spline of the unit for projection through the outer end face of the side wall into the framing for anchoring the unit to the framing to preclude transverse flexing of the unit in the opposite direction by weather pressure; comprising an elongated body provided with end sections and formed between said sections with a relatively long portion and having oppositely disposed substantially flat pane engaging inner and spline engaging outer faces adapted for sliding engagement with and between the pane and spline, respectively, one of said end sections adapted to be encased in the side wall and being laterally offset outwardly with respect to said portion, said one of said end sections constituting an anchoring section for projection through the outer end face into the framing for anchoring engagement therewith to preclude flexing of said sash unit in said opposite direction when so projected, the other end section extending at an angle relative to said portion and outwardly from said outer face, said other end section constituting a fingerpiece for effecting said projection and adapted to terminate within a zone defined laterally by the spline.
